CLAIM

What is claimed is an ornamental design for a virtual reality headset, as shown and described herein.

DESCRIPTION

FIG. 1 is a front perspective view of a virtual reality headset; FIG. 2 is a top view thereof;

FIG. 3 is a bottom view thereof;

FIG. 4 is a front-side view thereof;

FIG. 5 is a left-side view thereof;

FIG. 6 is a right-side view thereof; and,

FIG. 7 is a back-side view thereof.

Any broken lines in the drawings are for purposes of illustrating portions of the controller and form no part of the claimed design.

1 Claim, 7 Drawing Sheets
